CLAIM

The ornamental design for a cover for an automobile-type cigarette lighter receptacle, as shown and described.

DESCRIPTION

FIG. 1 is a front elevation view of a cover for an automobile-type cigarette lighter receptacle showing my new design, the back elevation view being the same; FIG. 2 is a right-side elevation view thereof, the left side elevation view being the same;

FIG. 3 is a top plan view thereof;

FIG. 4 is a bottom plan view thereof;

FIG. 5 is a bottom perspective view thereof.
